United States Patent Office

Des. 208,296
Patented Aug. 15, 1967

208,296

LOW PROFILE TELEPHONE STATION

Keith D. Bartley, Indianapolis, Ind., Henry Dreyfuss, South Pasadena, Calif., and Donald M. Genaro, Haworth, N.J., assignors to Bell Telephone Laboratories, Incorporated, Berkeley Heights, N.J., a corporation of New York

Filed Oct. 6, 1966, Ser. No. 4,176

Term of patent 14 years

(Cl. D13—1)

FIG. 1

FIG. 2

FIG. 1 is a frontal perspective of the station taken from the right side; and

FIG. 2 is a frontal perspective taken from the left side. The back of the station is unornamented.

The phone is shown in broken lines in FIG. 1 for illustrative purposes only.

We claim:

The ornamental design for a low profile telephone station, as shown and described.
